UNITED STATES PATENT OFFICE.

ROBERT E. BROWN, OF OLEAN, NEW YORK.

COMBINATION TOILET ARTICLE.

1,343,959.

Specification of Letters Patent. Patented June 22, 1920.

Application filed January 7, 1918. Serial No. 210,728.

To all whom it may concern:

Be it known that I, ROBERT E. BROWN, a citizen of the United States, residing at Olean, in the county of Cattaraugus and State of New York, have invented certain new and useful Improvements in Combination Toilet Articles, of which the following is a specification.

This invention relates to combination 10 toilet articles and more particularly to a combined razor hone, razor strop, razor carrier, and mirror, one aim of the invention being to so construct and arrange the component elements of the article that the article as a whole will be neat and compact thus especially recommending it for use by soldiers, sailors and travelers.

The article embodying the present invention includes a stock which comprises 20 hingedly connected sections and it is one object of the invention to provide a hinge connection between the said sections of such a character that when the sections are relatively closed or brought together, the strop 25 element of the article will be drawn taut throughout the length of its portion which is to be used as a razor strop so that by merely closing the sections of the stock, the strop will be placed under proper tension. 30 The invention also contemplates the utilization of one end of the strop as a means for holding the sections of the stock closed.

Another aim of the invention is to provide means for separably connecting one end 35 of the strop element with one of the sections of the stock in such a manner that should the strop become so stretched through constant use as to not be properly tensioned when the sections of the stock are closed, the slack may be taken up through the medium 40 of said connection for the said end of the strop.

Another aim of the invention is to construct the meeting sides of the sections of 45 the stock so as to house and adequately protect a razor disposed therebetween.

The invention also has as its object the provision, in an article of this class, of a metallic mirror carried by one of the sections of the stock and adapted to be normally housed, when not in use, beneath the strop of the article so as to be protected, and adapted further when to be made use of, to be swung to position extending beyond 50 one side of the stock, the stock at such time constituting a firm base or support for the

mirror. The invention further has as its object the utilization of the ends of the strop as a supporting surface for the article of such nature that when the article is disposed upon a flat surface with its hone supporting face lowermost, the hone will be supported in spaced relation to the said surface so as not to become scratched or otherwise injured and so that furthermore, if the 60 surface be a polished one it will not be scratched by the contact of the hone therewith.

In the accompanying drawings:

Figure 1 is a perspective view of the article 70 embodying the present invention closed and in position for the stropping of a razor;

Fig. 2 is a similar view but illustrating the article open, or in other words, the sections of the stock swung apart;

Fig. 3 is a vertical longitudinal sectional view through the article closed;

Fig. 4 is a perspective view of the article 80 illustrating the manner in which the same is to be arranged when using the mirror.

The article embodying the present invention includes a stock which is indicated in general by the numeral 1 and said stock comprises the sections 2 and 3 which may be formed from wood or any other suitable material and which are of oblong form. The inner or meeting faces of the said sections 2 and 3, indicated in general by the numerals 4 and 5 respectively, are flat so that when the sections are swung together or closed 90 these faces of the sections will snugly fit against each other. At one end of the stock, however, the said faces of the sections 2 and 3 are beveled or inclined, as indicated by the numeral 6, in outwardly diverging 95 planes and secured to the bevels 6 are the leaves 7 of one or more hinges 8 which serve to hingedly connect the sections so that they may be swung to the closed position shown in Figs. 1, 3 and 4 of the drawings, 100 or to the open position shown in Fig. 2. In order that a razor, indicated by the reference letter R, may be housed between the sections 2 and 3 of the stock 1, the faces 4 and 5 of the said sections are recessed as 105 indicated by the numeral 9, so as to form a relatively long and narrow pocket to receive the razor, the recesses forming the pocket being each preferably provided with a lining 10 of any desired material; such for example as plush or, if desired, a water-proof or moisture excluding material. By refer-

ence to Fig. 3 of the drawings it will be observed that when the sections 2 and 3 of the stock are swung together upon the hinge 8 to bring their faces 4 and 5 into contact, the pocket will be closed so as to completely house the razor R.

As before stated the faces 4 and 5 of the sections 2 and 3 are flat, but by reference to the drawings it will be observed that the outer faces of sections 2 and 3 are depressed, as indicated respectively by the numerals 11 and 12, the depressions extending from side to side of the said outer faces of the sections and longitudinally of the said faces throughout nearly their entire length but terminating short of the ends of the sections. A hone 13 is set into the outer face of the section 3 in the depression 12 and the working face of this hone occupies a plane lying inwardly of a plane touching the said outer face of the said section 3 at the ends of the depression so that when the article is disposed upon a surface in the position shown in Fig. 3 of the drawings, the said working face of the hone will be spaced above said surface.

As stated above the depressions 11 and 12 terminate short of the ends of the sections in which they are formed and as a result shoulders 14 and 15 are formed upon the outer face of the section 2, respectively at the hinged and free ends of the section, and similar shoulders 16 and 17 are formed upon the outer face of the section 3, respectively at the hinged and free ends of the said section. The outer surfaces of the shoulders 14, 15, 16 and 17 are rounded in the direction of length of the stock, the rounded surfaces of the shoulders 14 and 16 extending between the adjacent ends of the depressions 11 and 12, respectively, and the outer ends of the beveled surfaces 6, and the rounded faces of the shoulders 15 and 17 extending between the said depressions in the respective sections and the adjacent ends of the faces 4 and 5 of the respective sections. Thus in the latter instance at the end of the stock opposite the end at which the hinge 8 is located, there is provided a substantially continuously rounded surface extending eccentrically to the hinge joint and in an arc the center of which lies at a point in the line of the meeting faces of the sections 2 and 3 of the stock. The numeral 18 indicates a strop of leather or other suitable material and at one end this strop is passed over the curved faces of the shoulders 15 and 17, as shown in Fig. 3 of the drawings, and the said strop is secured adjacent this terminal, to the free end of the section 2 of the stock by means of a transverse plate 19, and securing elements 20, the plate 19 being disposed against the outer face of the strop and the securing elements being driven through openings in the said

plate, through the strop, and into the shoulder 15 of the section 2. In this manner the said end of the strop is permanently fixed with relation to the shoulder 15 and the end portion of the strop beyond its point of attachment to the said shoulder constituting a flap 21 which carries the socket member 22 of a snap fastening device, the stud member of which device is indicated by the numeral 23, and is secured upon the section 3 of the stock directly inwardly of the shoulder 17 and in the depression 12. It will now be understood that when the sections 2 and 3 have been swung to closed position, they may be held in such position by bringing the flap 21 over the shoulder 17 and engaging the socket member 22 with the stud member 23. From its point of attachment to the shoulder 15 of the section 2 of the stock, the strop 18 is led longitudinally above the section 2 and the depression 11 therein and at its opposite end is passed over the rounded faces of the shoulders 14 and 16 and secured at its extremity to the under side or outer face of the section 3 by means of a clamp device which will now be described. The clamp device above referred to comprises a jaw 24 and a jaw 25 and the said jaw 24 is disposed against the said outer face of the section 3 of the stock in the depression 12 and is permanently secured in place by means of fastening elements 26. The said clamp device is formed from sheet metal and initially the jaws 24 and 25 are relatively spread apart. At its free or transverse edge, the jaw 25 is formed with teeth 27, and after the terminal of the strop 18 has been inserted between the jaws, the jaw 25 is struck down toward the jaw 24 so as to cause the terminal of the strop to be gripped by the jaws and also to cause the teeth 27 to bite into the strop. From the foregoing it will be understood that due to the peculiar hinge connection between the sections 2 and 3 of the stock 1, the rounded faces of the shoulders 14 and 16 will be brought toward each other when the sections 2 and 3 are swung apart, and on the other hand caused to move away from each other as the sections are swung to closed position. Thus when the sections are swung apart, as shown in Fig. 2 of the drawings, the strop 18 will be relieved of tension, but when the sections are swung closed, the rounded faces of the shoulders 14 and 16 will ride against the inner surface of the strop 18 in a manner to draw the strop tight between its points of attachment to the sections 2 and 3 respectively. Thus the portion of the strop which extends between the shoulders 14 and 15 will be held taut and at the proper tension for stropping of a razor, when the sections 2 and 3 are in the closed position shown in Figs. 1 and 3 of the drawings. Should the strop become stretched so

that its working portion will not be drawn sufficiently taut when the sections 2 and 3 are closed, this may be remedied by prying up the jaw 25 of the clamping device above 5 described, disengaging the terminal portion of the strop held thereby, cutting off a short length of the strop at its terminal, and then reinserting the terminal of the strop into the clamp and closing down the jaw 25. 10 It will further be apparent that as the strop, in the closed position of the sections 2 and 3, is under tension, when the flap 21 is disengaged from the section 3, the resiliency of the strop will act to hold the sections 2 and 15 3 apart so as to permit of ready access to the pocket in which the razor is contained. It will also be understood by reference to Fig. 3 of the drawings that the portions of the strop which extend beneath the shoulders 20 16 and 17 constitute cushioned rests for the article when the same is disposed upon a polished surface and prevent scratching of said surface and at the same time prevent the working face of the hone 13 coming 25 in contact with such surface.

The mirror element of the article comprises a metallic oblong plate 28 having a polished or mirror face 29, and this plate is of such dimensions as to be adapted to be 30 housed within the depression 11 and between the face of the depression and the portion of the strop 18 which extends above the said depression. A pivot pin or screw 30 is fitted through an opening formed in the 35 plate 28 near one corner of the plate and in this manner the plate is swiveled to the outer face of the section 2 of the stock and is adapted to be swung to position lying wholly within the depression 11, as shown in 40 Figs. 1, 2 and 3 of the drawings, or to a position extending upwardly from one side of the stock, as shown in Fig. 4 of the drawings. In order that the mirror may be held in either of the positions desired, the face 45 of the depression 11 is formed with spaced sockets 31 and 32 located in a line which is an arc having at its center the pivot 30, and the mirror plate 28 is indented to form a shallow protuberance 33 designed to seat in 50 either of the sockets 31 or 32, the plate being sufficiently resilient to permit of the protuberance riding into or out of the socket as the plate is swung upon its pivot. It will be understood, of course, that when 55 the plate has been swung to bring the protuberance into engagement in the socket 31, the said mirror plate will be housed within the depression 11 and on the other hand when the mirror plate has been swung to 60 bring the protuberance into engagement in the socket 32, the plate will be held in the upright position shown in Fig. 4 of the

drawings, the stock at such time constituting a solid and substantial base for the mirror plate.

65

Having thus described the invention, what is claimed as new is:

1. In a device of the class described, a stock comprising members hingedly connected at one end, a strop secured to one of said members at a point remote from the hinged end thereof and passed around the hinged ends of the said members and secured to the other one of said members, the non-contacting faces of the said members at their hinged ends being provided with shoulders engaging the inner surface of the strop and rounded eccentrically with respect to the hinge joint.

2. In a device of the class described, a stock comprising members hingedly connected at one end, a strop secured to one of said members at a point remote from the hinged end thereof and passed around the hinged ends of the said members and secured to the other one of said members inwardly of the hinged end of the latter, the strop beyond its first-mentioned point of attachment having a flap portion to engage around the free ends of the said members, 90 and coacting locking means upon the said flap portion and the second-mentioned member.

3. In a device of the class described, a stock comprising members having mutually 95 abutting faces and having their faces at one end outwardly beveled, a hinge having its leaves secured to the bevels of the said faces and hingedly connecting the said members at their said ends, the outer faces of the 100 members at their hinged ends having rounded shoulders, and a strop secured to the free end of one of the members and extending longitudinally above the said member and thence about the said rounded 105 shoulders and secured at its other end to the other end of the said members inwardly of the said hinge.

4. In a device of the class described, a stock comprising members hingedly connected at one end, a strop secured to the outer face of one of the members at a point remote from the hinged end thereof and passed around the hinged ends of the said members and secured to the other one of 110 said members inwardly of the hinged end thereof, the first mentioned member being provided upon its said face at its said hinged end with a shoulder having a portion 115 eccentric to the hinge joint to engage the inner side of the adjacent portion of the strop when the members are closed.

In testimony whereof I affix my signature.

ROBERT E. BROWN. [L.S.]
